AUTOMATIC CLOSER FOR A SLIDING SCREEN DOOR

Luis F. Guerrero, Los Angeles, Calif.
(10632 Garden Grove Ave., Northridge, Calif. 91324)

Filed Aug. 29, 1973, Ser. No. 392,627

Term of patent 14 years

Int. Cl. D8—09

U.S. Cl. D8—203

FIG. 1 is a perspective view of an automatic closer for a sliding screen door showing my new design;

FIG. 2 is a rear view thereof;

FIG. 3 is a front view thereof;

FIG. 4 is a side view thereof;

FIG. 5 is a top view thereof; and

FIG. 6 is a bottom view thereof.

I claim:

The ornamental design for an automatic closer for a sliding screen door, substantially as shown.
